(57) **CLAIM**

The ornamental design for a forklift fork tip, as shown and described.

DESCRIPTION

FIG. 1 is a top, front isometric view of a forklift fork tip showing my new design;

FIG. 2 is a bottom, rear isometric view thereof;

FIG. 3 is an enlarged top, front isometric view thereof;

FIG. 4 is a left side elevational view, the right side being a mirror image thereof;

FIG. 5 is an enlarged top plan view thereof;

FIG. 6 is an enlarged front elevational view thereof; and, FIG. 7 is an enlarged bottom plan view thereof.

The broken line showing of a forklift fork is included for the purpose of illustrating environment and forms no part of the claimed design. The broken lines immediately adjacent to the shaded areas of the drawing represent unclaimed boundaries of the design.
